UNITED STATES PATENT OFFICE.

LEO J. MOLLOY, OF BUFFALO, NEW YORK.

SET-SCREW.

No. 907,160.

Specification of Letters Patent.

Patented Dec. 22, 1908.

Application filed September 14, 1908. Serial No. 452,988.

To all whom it may concern:

Be it known that I, LEO J. MOLLOY, a citizen of the United States, residing at Buffalo, in the county of Erie and State of New York, have invented certain new and useful Improvements in Set-Screws, of which the following is a specification.

This invention relates to an improved set-screw, and it has for its object the production of a screw particularly adapted for securing conduit-pipes in condulets but it may also be used generally where set-screws are employed and impinge with their ends against a hard surface.

It also has for its object the production of a set-screw which will bore into a hard surface and will expand radially in the region of the end thread or threads, so as to impinge forcibly against the coöperating threads of the tapped opening into which the screw is threaded.

A still further object is, the production of a set-screw comprising two members so related, that one serves to expand the end of the other and prevent loosening of the screw by jarring of the parts.

With these and other objects in view, the invention consists of an externally-threaded outer member and an internal impinging-member held by said outer member against the object fastened.

It also consists in the construction, arrangement, and combination of the parts constituting said set-screw as hereinafter described and particularly pointed out in the subjoined claims.

In the drawings,—Figure 1 is a sectional elevation of an electric wire-conduit showing the conduit-pipe fastened into a condulet by means of my improved set-screw. Fig. 2 is a horizontal section taken on line 2—2, Fig. 1. Fig. 3 is an enlarged sectional elevation of my improved set-screw. Fig. 4 is an enlarged longitudinal section of the outer member of the same. Fig. 5 is an enlarged elevation of the inner impinging member.

Referring now to the drawings in detail, like letters of reference refer to like parts in the several figures.

Experience has shown that set-screws of the common type when used to impinge against a hard surface, will not, in many cases, withstand the slight jar to which they are subjected, without becoming loosened and the parts intended to be secured thereby becoming unfastened, and for this reason, it

has been the practice in connecting conduit-pipes to condulets to externally thread the ends of said pipes and screw the same into the internally threaded ends of the condulets. This is not only expensive, but inconvenient as well, on account of the distances between the condulets being unequal so that the conduit-pipes must be cut to the lengths required and then threaded for connection with the condulets. Furthermore, the conduit pipes are enameled and by gripping the same with a pipe-wrench in order to fasten them within the threaded ends of the condulets, the enamel will become chipped and otherwise marred. While I have particularly designed this set-screw for the connection of conduit-pipes to condulets, it may be used for fastening pulleys upon shafts and wherever set-screws are employed; particularly, where such screws are subjected to jar and there is a tendency of the same becoming loosened.

To show the application of this improved set-screw, I have illustrated a conduit for electric wires in which A represents the condulet having a lateral extension B, and into the said extension and the ends of said condulet which are smooth bored, I insert conduit-pipes C, the inserted ends of which are unthreaded.

D are the circuit-wires passing through the conduit and joined within the condulet. The ends of the conduit pipes are fastened in the condulet by means of my improved set-screw. This set-screw comprises an outer-member E having a central longitudinal bore e extending from end to end thereof and beveled or countersunk at the inner end of said bore, as shown at e¹. Said outer member also has the usual square head e² at its outer end and it is externally threaded, at at e³, similar to the ordinary set-screw; said outer member is threaded into a tapped opening a formed in the condulet. Fitting in said longitudinal bore e is an impinging member F somewhat longer than the outer member so as to project from opposite ends thereof. The inner end of said impinging-member has an enlarged oppositely tapered head f to provide a flaring expander-portion f¹ which cooperates with the countersunk end e¹ of the bore e and a pointed or conical impinging portion f² which is adapted to be forced into the metal of the conduit pipe, in the manner shown in Fig. 2.

In using the set-screw to fasten an object,

the impinging member is thrust into the externally-threaded outer member so that it projects from both ends of the latter, as shown in Fig. 3. With the two parts thus 5 arranged, the set-screw is threaded into the tapped opening and by reason of the expander-portion f^1 being seated against the countersunk portion of the bore e , the impinging-member is forced against the object 10 to be fastened; but in order that assurance is had of a secure fastening, the outer projecting end of said member is to be struck with a hammer or other object so as to drive the pointed or conical inner end thereof into the 15 metal of the object fastened. By striking the impinging-member, the expander-portion f^1 thereof is forced away from the countersunk end of the bore e formed in said outer member, thus permitting the latter to be 20 screwed farther into the tapped opening. When the pointed or conical end of the impinging-member is driven into the metal of the object fastened to the extent desired, the outer member is screwed tight against the 25 expander portion f^1 whereby the inner end of said outer member is expanded so that the threads in the region of the counter-sunk part e^1 are forcibly crowded into the co-operating threads of the tapped opening; thus securing a positive fastening and at the same 30 time preventing accidental unscrewing of the outer-member.

Having thus described my invention, what I claim is,—

- 35 1. A set-screw comprising a hollow threaded outer member and an impinging-member fitting into said outer member and having an enlarged portion against which the inner end of said outer member bears, said impinging- 40 member being adapted to impinge against the object to be fastened.

2. A set-screw comprising an externally-threaded outer member having a head at its outer end and provided with a longitudinal bore, and an impinging-member fitting into said bore and having an enlarged and pointed end portion against which the inner end of said outer member bears. 45

3. A set-screw comprising an outer externally-threaded member provided with a longitudinal bore, and an impinging-member fitting into said bore and extending from opposite ends of said outer member, said impinging-member having a pointed enlargement at its inner end against which the inner end of 55 said outer member bears. 50

4. A set-screw comprising an externally-threaded outer member provided with a central longitudinal bore beveled at one end to form a countersunk portion and an impinging-member fitting into said bore and extending from opposite ends of said outer member, said impinging-member having an oppositely-tapered enlargement providing an expander-portion fitting into the countersunk portion of said bore and a conical impinging portion adapted to be driven into the metal of the object fastened. 60 65

5. A set-screw comprising an externally-threaded member provided with a central longitudinal bore, and an impinging-member fitting into said bore and provided with 70 means for expanding the inner end of said outer member.

In testimony whereof, I have affixed my 75 signature in the presence of two subscribing witnesses.

LEO J. MOLLOY.
